Specification for Design.

Patented Aug. 2, 1921.

Application filed February 5, 1920. Serial No. 356,409. Term of patent 7 years.

To all whom it may concern:

Be it known that I, WALTER E. SANDERS, a citizen of the United States of America, and a resident of the city of Trenton, county of Mercer, and State of New Jersey, have invented a new, original, and ornamental Design for Heel-Rests, of which the following is a specification, reference being had to the accompanying drawing, forming part thereof.

In the drawings, Figure 1 is a plan view and Fig. 2 is a longitudinal section of a heel rest showing my design.

I claim as my invention:

The ornamental design for a heel rest as shown.

WALTER E. SANDERS.
